UNITED STATES PATENT OFFICE.

LEONARD H. WHEELER, OF CHICAGO, ILLINOIS, ASSIGNOR TO STEWART-WARNER SPEEDOMETER CORPORATION, OF CHICAGO, ILLINOIS, A CORPORATION OF VIRGINIA.

VACUUM FEED DEVICE.

Application filed April 15, 1922. Serial No. 553,195.

To all whom it may concern:

Be it known that I, LEONARD H. WHEELER, a citizen of the United States, residing in the city of Chicago, in the county of Cook 5 and State of Illinois, have invented certain new and useful Improvements in Vacuum Feed Devices, of which the following is a specification, reference being had to the accompanying drawings, forming a part 10 thereof.

The purpose of this invention is to provide a compact form of vacuum feed tank or apparatus adapted for lifting liquid, such as liquid fuel, from a low level supply reservoir to an elevated receptacle provided as a 15 part of the outfit and from which the liquid is permitted to flow by gravity to the point of use, such as the carburetor of an automobile engine. The device is particularly 20 designed to include a sight glass associated with the elevated receptacle and arranged to be mounted in the instrument board or front wall of the driver's compartment of the vehicle for indicating the presence and quantity 25 of liquid in the elevated chamber. The invention consists in various features of construction and their combination, hereinafter described and shown in the drawings, as indicated by the claims.

30 In the drawings:—

Figure 1 is a vertical sectional view of a vacuum feed device embodying this invention, section being taken substantially as indicated at line, 1—1, on Figure 2.

35 Figure 2 is a transverse vertical section of the same taken as indicated at line, 2—2, on Figure 1.

Figure 3 is a horizontal section taken as indicated at line, 3—3, on Figure 1.

40 Figure 4 is a transverse section at right angles to Figure 2 as indicated at line, 4—4, on Figure 1.

The principle of operation of the vacuum feed device embodying this invention is substantially similar to that of the structure shown in the Webb Jay Patent No. 1,125,549 45 dated January 19, 1915, and needs no elaborate explanation. The device comprises two receptacles or chambers, preferably disposed

one within the other, the outer chamber, 1, 50 serving as a temporary elevated supply tank for the liquid and the inner chamber, 2, being subjected alternately to suction or partial vacuum and atmospheric pressure for drawing in liquid from a low level supply tank, 55 not shown, and discharging it to the outer chamber, 1. As shown, the device is designed for manufacture by die casting the larger parts and the chamber, 2, is suspended within the chamber, 1, with a clearance space, 3, 60 serving to permit expansion of the liquid and vapor in the chamber, 1, upon increase of temperature.

For mounting the device the chamber, 1, 65 is provided with lugs, 4, apertured to receive suitable screws, 5, set into the rear face of the partition wall or instrument board indicated at A. A top plate or cover, 6, is assembled with the chambers, 1 and 2, by means of fastening screws, 7, extending 70 through the upper marginal flanges of said parts; and said top plate has formed upon it passages including the suction or vacuum passage, 8, the liquid supply intake passage, 9, and the atmospheric inlet, 10, as shown 75 respectively in Figures 1, 4 and 2. The suction passage, 8, is controlled by a valve, 11, and the atmospheric vent is controlled by a valve, 12, said valves being operated by the change in level of liquid in the chamber, 3, 80 acting through a float, 13, slidably guided upon a stem, 14, upon which it has a limited range of travel between stops, 15 and 16. Said stem is engaged at its upper end with a bifurcated lever member, 17, whose arms, 85 18, are fulcrumed upon studs, 19, set into brackets, 20, which are formed integrally with the top plate, 6, and depend therefrom within the chamber, 2.

The lever member, 17, is yieldingly held 90 at either limit of its range of swing by means of a coiled spring, 21, hitched to the lever at an aperture, 22, therein, and anchored to a post, 23, depending from the top plate, 6; the bifurcated form of the 95 member, 17, permits the spring, 21, to be accommodated between its arms, 18, and to pass above or below the axis of the fulcrum

studs, 19, as the lever swings up or down. At the portion remote from the fulcrum axis, the member, 17, is apertured to engage the stems, 11^a and 12^a, of the suction and atmosphere valves respectively.

The lower end of the float stem, 14, is guided in a suitable stamped spider, 24, pressed into a recess in the bottom of the chamber, 2. Upon reversal of the valves—
10 that is, closing of the suction valve, 11, and opening of the atmosphere valve, 12, the liquid in the chamber, 2, is discharged therefrom through a nipple, 25, formed below the spider, 24, and exteriorly threaded to receive a flanged valve seat member, 26, over which the valve cage, 27, is tightly fitted. During the filling period of the chamber, 2, the discharge opening is closed by a disk valve, 28, which is held to the seat, 27, by
15 the suction in the chamber, 22, but upon cessation of the suction said valve drops through a short distance limited by the length of its supporting lugs, 29, which are positioned to rest upon the in-turned flange, 30, of the cage, 27, during discharge of the liquid from the chamber, 2, into the chamber, 1. From the chamber, 1, the liquid will flow by gravity as required, a suitable connecting nipple, 31, being formed in the bottom wall of said chamber for attachment of a connecting pipe.

Preferably, to prevent the in-flowing liquid entering at 9, from interfering with the operation of the float, 13, said liquid is
35 conducted past the float by a pipe, 32, to the lower portion of the chamber, 2, below the float, 13, as indicated in Figures 3 and 4. It should be understood that the outer chamber, 1, is kept constantly at atmospheric pressure, being vented through the space, 3, which may communicate with the atmospheric intake, 10, by way of a pipe or duct, 33, as shown in Figure 2.

To apprise the operator of the engine of
45 the presence and quantity of liquid in the chamber, 1, the latter is preferably formed with a cylindrical flange, 34, extending from the flat wall of the chamber having the mounting lugs, 4, for securing it against the partition or instrument panel, A. The outer end of the flange, 34, is threaded to receive a bezel ring, 35, for clamping a sight glass or window, 36, over the end of the flange with suitable packing interposed to render it liquid-tight while thus permitting the liquid in the chamber to be viewed at all times.

I claim:—

1. In a vacuum feed device comprising a vacuum chamber into which liquid is drawn by suction and a reserve chamber into which it is periodically released for gravity flow to the point of use, said outer chamber being formed with a laterally projecting flange adapted to protrude through an opening in
60 a supporting partition wall, dash board, or

the like, and a transparent closure secured to said flange forming a sight opening through which the contents of the reserve chamber may be observed.

2. In the combination defined in claim 1,
70 said flange being annular and the closure comprising a circular glass fitted against the outer end of the flange with a packing cushion interposed, and a bezel ring screwed onto the flange for clamping the glass in
75 place.

3. In a vacuum feed device including a vacuum chamber having a suction port and an atmosphere port, a valve for each port and means for actuating said valves simultaneously, comprising a bifurcated lever having its two arms fulcrumed on a pair of laterally supported brackets; a pull spring hitched to the lever between its arms and extending between the fulcrum brackets to an
80 anchorage beyond them; means for connecting both valves to the lever at a distance from its fulcrum axis, and a float in the chamber operatively engaged with the lever for actuating the valves.

4. In the combination defined in claim 3,
85 said valves being connected to the lever both at the same side of the fulcrum axis of said lever.

5. In the combination defined in claim 4,
90 said valves being connected to the lever at equal distances from its fulcrum axis adjacent each other at the same side of said axis.

6. In the combination defined in claim 4,
100 said lever having a transverse part connecting the two arms which extend to fulcrum brackets; a float in the chamber having a stem engaging the said transverse portion of the lever, and the valves being connected to said portion at substantially the same distance from the fulcrum axis.

7. In a vacuum feed device comprising a vacuum chamber into which liquid is drawn by suction, and a reserve chamber into which it is periodically discharged from the vacuum chamber for gravity flow to the point of use, the discharge port of said vacuum chamber being formed in a threaded nipple with a flat valve seat member facing downwardly, and having an upwardly extending threaded annular flange engaged with said nipple, a valve disk disposed below the seat and provided with depending lugs, and a valve cage comprising a sleeve portion fitted tightly over the seat member and formed with an in-turned flange extending under said seat in spaced relation thereto for engaging the lugs of the valve disk to support the latter and limit its range of movement away from its seat.

8. In a vacuum feed device comprising a vacuum chamber into which liquid is drawn by suction, and a reserve chamber into which it is periodically discharged for gravity flow to the point of use, a
130

discharge valve for the vacuum chamber comprising a downwardly facing seat; a valve disk disposed below the seat having depending lugs and a valve cage comprising

5 a sleeve portion extending around the seat member and formed with an in-turned flange disposed in a plane below said seat and

spaced therefrom under the lugs of the valve disk for supporting the valve when unseated and limiting its range of movement. 10

In testimony whereof, I have hereunto set my hand at Chicago, Illinois, this 12th day of April, 1922.

LEONARD H. WHEELER.
